UNITED STATES PATENT OFFICE

2,532,572

DEVICE FOR ATTRACTING ATTENTION TO
BILLBOARDS

Reuben G. Reeves, Camden, N. J.

Application September 19, 1947, Serial No. 774,935

1. Claim. (Cl. 272—31)

1

The subject-matter of this application relates to advertising sign boards of the class designated as bill boards. Generally stated, my invention has for its object to provide means of a movable nature designed to attract the attention of passers-by and more specifically to an arrangement of parts mounted in conjunction with a highway sign which is caused to revolve by a current of air.

Another object of my invention is the provision of a rotatable framework, which may be mounted atop a signboard located in an open space such as the country side, and carries a series of silhouettes of the hulls of boats equipped with sails which act to impel the framework and by movement of the latter and the fluttering of the sails will attract attention in their direction and consequently add an advertising value to the sign on which the apparatus is mounted.

A still further object of my invention is to construct an advertising device of the above character in such a manner that the parts thereof may be assembled in the first instance in a knock-down condition for shipment and subsequently readily set up in the field without the use of special tools.

To these and other ends my invention consists of further improvements all of which will be fully described in the following specification, the novel features thereof being set forth in the appended claims.

In the drawings:

Figure 1 is an elevational view of a highway sign showing a visual attracting device embodying my invention applied thereto.

Figure 2 is a top plan view thereof.

Figure 3 is a detail view of ship silhouette.

Figure 4 is an enlarged detail view showing the center post, its bearing and the struts and suspenders connected to said post.

Figure 5 is a horizontal detail plan view of the central strut plate as seen on section-line 5—5 of Fig. 4.

Figure 6 is a detail view showing the outer end of one of the struts and the manner of connecting the ship silhouette thereto, and,

Figure 7 is a horizontal plan view of the suspender connecting plate as the same appears when viewed on the section line 7—7 of Fig. 4.

Similar reference characters in the several figures indicate similar parts.

In illustrating my invention I have shown the device for attracting attention in connection with a signboard 10 of suitable dimensions mounted on a framework for installation and

2

use in open spaces, such as a field along a highway. The supporting framework comprises similar front and rear sections each having diagonally disposed leg portions 11 and 12 connected at their upper ends by horizontal top portions 13, 14. The two sets of legs are anchored at their lower ends in concrete blocks 11a—12a and are inclined toward each at their upper ends where they are connected by cross bars 15, 16. The signboard 10 is supported on the frame at a suitable elevation by connecting its lower edge to a pair of the frame legs and because of their angular disposition I secure its upper edge by a pair of arms 19a projecting outwardly from the top of the frame. If desired the ends of the cross bars 15—16 may be extended for this purpose. Thus it will be seen that above the top of the signboard there is a rectangular area which may be utilized as a platform which I make in skeleton form by extending thereacross two rails 17—18. The base for the latter comprises a plate 19 bolted to said rails carrying a hub 20 in which a vertical shaft 21 is stepped and supported for free rotational movement in the hub. Anti-friction bearings are provided for the post by seating its lower end on a ball race 22 and guiding a more elevated point thereon in a similar but larger bearing 23 fitted in a recess 20a at the top of the hub, as shown in Fig. 4.

On the shaft 21, immediately above its upper bearing 23, is a circular plate 24 having radial projections 25 which are rectangular in cross section. There are six of these projections each of which carries the inner end of a strut 26 formed of pipe which is swaged on two sides to fit over the projection as indicated at 27. This method of connecting the parts is a simple means of preventing the struts from turning. At the upper end of the shaft is a circular plate 28 having a central aperture fitting a reduced portion at the top of the shaft to which it is secured by a nut 29. In this plate are a series of peripheral apertures which receive the hooked or fingered ends 30 of a series of suspender rods 31, of which there is one corresponding to each of the struts 26 and to which they are respectively connected near the outer ends of the struts by passing the hooked ends 32 of each suspender through an eye bolt 33.

Extending transversely of the outer ends of the struts and bolted thereto are rectangular plates 34 provided with apertures at their extremities into which are hooked the bent ends of tie rods 35. In one of the latter I place a turn-buckle 35a

which when drawn up renders rigid the framework composed of the several struts 26 and the central plate 24.

On the outer end of each strut 26 I mount a vertical plate 36 having the general outline of the hull of a sailing vessel, which in the present instance is shown as a cat boat. The plate is fixed rigidly by providing on its lower edge a flange 37 which extends inwardly over the plate 34 and together therewith is secured to the strut by two bolts 38, 39. It will be noted that the flange 37 is larger than the underlying plate 34 and extends over the contiguous ends of two of the tie rods 35. This prevents displacement of the rods and the bearing of the extremities of the flange 37 thereon serves to prevent tilting of the silhouette plates in relation to the horizontal plane in which they rotate.

Each silhouette plate carries at its forward end a mast 40 on which is rigged a main sail 41 having a boom 42. The latter is free to swing a limited distance on its pivoted point on the mast and in lieu of the usual sheet rope I employ a swivel link connection 43 between the stern of the ship and the rear end of the boom which permits the latter to swing from one side of the mast to the other as the turntable, on which the several dummy ships are mounted, revolves. Only a slight wind pressure on one or more of the sails is required to rotate the turntable, the speed of which varies with such pressure causing the continuous movement of the apparatus to attract the attention of persons who may be travelling within view of the sign 10 on which the apparatus is mounted.

I claim:

An attachment for bill boards comprising a base plate adapted to be secured to a bill board, a vertically extending hub fixed to said plate and having an axial bore therein, the upper surface of the hub having a cylindrical recess therein, a vertical post having its lower end journaled in the hub bore, ball bearing means resting on said plate and contacting the end of the post for sustaining said post, a collar on the post and fitting within said hub recess, anti-friction bearings within said recess contacting said collar to laterally support the post, a plate mounted on the post above the hub having radial projections rectangular in cross section, radially extending tubular struts having their inner ends swaged to embrace said projection, a collar attached to the upper end of the post having a plurality of vertical apertures therein, radially extending suspension members corresponding in number with the struts and having hooked inner ends adapted to fit in said vertical apertures, said members having hooked outer ends for detachably connecting the members to said struts.

REUBEN G. REEVES.
